Attorney.

UNITED STATES PATENT OFFICE.

FREDERICK W. HESSE, OF SANTA ROSA, CALIFORNIA.

UNDERSHOE.

SPECIFICATION forming part of Letters Patent No. 257,702, dated May 9, 1882.

Application filed March 13, 1882. (No model.)

To all whom it may concern:

Be it known that I, FREDERICK W. HESSE, a citizen of the United States, residing at Santa Rosa, in the county of Sonoma and State of California, have invented certain new and useful Improvements in Paper Undershoe, of which the following is a specification, reference being had therein to the accompanying drawings.

10 My invention relates to an undershoe or slipper constructed of paper with cloth facing, and designed to be worn next to the foot. It is not intended to take the place of a sock or stocking, although either of those articles may be dispensed with in favorable weather when my undershoe is used. The sock or stocking is intended to be drawn over said undershoe when the latter is placed on the foot.

15 The advantages arising from the use of the article are manifold. In the first place, as a sanitary measure, it can be kept on hand to be employed in case of a change in the weather, either wet or cold. By this means the feet can be easily kept at a uniform temperature.

20 The material of which it is composed—paper with cloth facing—is a non-conductor of heat. It therefore tends more readily than the wool, cotton, or leather to retain the heat imparted from the foot. The flexibility of said material

25 enables it to conform to the foot without inconvenience to the wearer. It must be obvious that it is a desirable article to be worn in taking long journeys by wagon, railway, or other means of conveyance. In addition to being

30 an auxiliary or temporary undershoe, it can be permanently and advantageously employed in certain latitudes. Another advantage derived from the use of the article lies in the fact that it serves to prevent the sock from coming in

35 contact with the foot, and thus protecting the one from the moisture of the other. By this means a sock can be worn longer than usual without becoming soiled from the foregoing cause.

40 The form of my invention and the material

of which it is composed render it a warm, comfortable, and inexpensive covering for the foot. In the use of the same overshoes may be dispensed with, inasmuch as sufficient warmth and dryness may be maintained in the foot 50 without their use. Of course they may be used in connection with my invention in rough weather; but for a slight snow or rain they can be dispensed with. The material composing the inner part of my undershoe is paper-pulp, and when shaped it is seamless. The pulp is provided with a thin facing of textile fabric. Said pulp and fabric may be united by placing adhesive material on the face of the pulp and then pressing the fabric against it; 55 or the union may be effected by other means.

I do not wish to confine myself to any process of uniting the parts.

In the accompanying drawings, Figure 1 is a perspective view of my invention. Fig. 2 is 65 a central longitudinal section, showing a foot equipped with my device; also, a sock and shoe in their respective order.

A represents a foot; B, the counter of my undershoe; C, the sole or bottom of same, and D the toe-covering. E is a stocking covering the foot A and undershoe. (Shown in Fig. 1.) F is the heel of the shoe proper; G, the sole; H, the upper, and B' the cloth facing.

I am aware that it is not new to construct a 71 shoe of paper combined with fabric, and I therefore do not claim such broadly; but

What I do claim, and desire to secure by Letters Patent, is—

As an improved article of manufacture, an 8c undershoe or slipper of seamless paper-pulp re-enforced by a facing of textile fabric, substantially as set forth, and for the purposes described.

In testimony whereof I affix my signature in 85 presence of two witnesses.

FREDERICK W. HESSE.

Witnesses:

JAMES H. NEYCE,

WILLIAM W. PORTER.
